UNITED STATES PATENT OFFICE.

HENRY ANTONIO MOOS, OF SEGUIN, TEXAS.

PACKING-CASE.

SPECIFICATION forming part of Letters Patent No. 406,145, dated July 2, 1889.

Application filed March 22, 1889. Serial No. 304,260. (No model.)

To all whom it may concern:

Be it known that I, HENRY ANTONIO Moos, a citizen of the United States, residing at Seguin, in the county of Guadalupe and State 5 of Texas, have invented a new and useful Improvement in Cases or Cabinets, of which the following is a specification.

This invention relates to cases or cabinets for packing and transporting articles that are 10 brittle and easily breakable, such as eggs, glassware, china, and the like; and it has for its object to provide a device or case containing a series of sub-compartments or boxes, each of which is provided with cells to receive 15 and hold the individual articles to be packed, thus affording great security in transportation and convenience in handling and in exposing the articles for sale.

The invention consists in the improved construction and combination of parts, which will 20 be hereinafter fully described, and pointed out in the claim.

In the drawings, Figure 1 is a perspective view of my improved packing-case with one 25 end open. Fig. 2 is a longitudinal vertical sectional view. Fig. 3 is a vertical transverse sectional view. Fig. 4 is a detail view of one of the cell-cases removed from the packing-case.

30 The same letters refer to the same parts in all the figures.

A designates the outer or packing case, which is preferably rectangular in shape, and provided with removable ends B B, the body 35 of the case comprising the sides C C, top D, and bottom E, all of which are permanently connected. The bottom E is provided near its ends with transverse grooves F F, and the ends of the top D are rabbeted, as shown at 40 G G. The ends B of the case are shouldered at their lower edges, as shown at H, to adapt their lower edges to enter the grooves F in the bottom of the case. The sides of the end pieces B are adapted to be fitted between the 45 sides of the case and the upper edges of said ends to enter the rabbets G in the top of the case. It will thus be seen that when the ends B are adjusted in position they are entirely flush with the ends of the body of the case. 50 When in position, the said ends may be se-

cured by means of spring-catches I, attached to the top D, and in order to render them easily removable the outer sides are provided with recesses J to enable them to be conveniently grasped.

The body of the case A is provided with a series of longitudinal shelves or partitions K K, of which there may be any desired number, and which serve to subdivide the said casing into compartments for the reception 60 of the cell-cases L L. The latter consist of boxes, which may be constructed of pasteboard or other suitable material, and which are provided with removable covers M. Each of the said cases is divided by means of partition-strips N, which may be of any suitable construction, into any desired number of cells, preferably a certain definite number—such as one, two, or three dozen—so that the contents of each cell-case shall be known.

The operation and advantages of my invention will be readily understood from the foregoing description, taken in connection with the drawings hereto annexed. The articles which are packed in the cell-cases are safely 75 protected from breakage, and the individual cell-cases, being separated by the horizontal partitions in the packing-case, are never liable to be crushed or jammed, to the injury of their contents. The individual cell-cases are 80 easily accessible by removing either end of the packing-case, and are convenient for exposing the contents for sale in an attractive manner. The said cell-cases also form 85 convenient packages, which may be sold or disposed of with their contents, and which, when emptied by the consumer, may be returned to the dealer and used over again.

I would have it understood that I do not 90 wish to limit myself to any particular construction of the individual cell-cases or of the cells therein. The said cells may be constructed of longitudinal and transverse vertical strips of paper or pasteboard intersecting each other and suitably connected, or of 95 a single vertical strip suitably folded; or they may be formed by a horizontal partition having openings to receive the individual articles that are to be packed. I would also have it understood that the horizontal partitions in 100

the packing-case may be dispensed with when desired, inasmuch as they are not always necessary to support the cell-cases.

Having thus described my invention, I
5 claim—

The combination, with a packing-case the bottom of which is provided with transverse grooves near the ends and the ends of the top of which are rabbeted on their under sides, 10 of the removable ends shouldered at their

lower edges, and the spring-catches attached to the upper side of the top of the case, substantially as set forth.

In testimony that I claim the foregoing as my own I have hereto affixed my signature in 15 presence of two witnesses.

HENRY ANTONIO MOOS.
